METHOD AND ARRANGEMENT FOR
SYNCHRONIZING OF PRINTING TELE-
GRAPHSHorst Rassow, Berlin-Friedenau, Germany,
assignor to Siemens & Halske, Aktiengesell-
schaft, Siemensstadt, near Berlin, Ger-
many, a corporation of GermanyApplication December 7, 1934, Serial No. 756,396
In Germany December 11, 1933

2 Claims. (Cl. 178—69.5)

The invention relates to a method and an arrangement for synchronizing of printing telegraph apparatus in which the individual letters, figures or other symbols are scanned or analyzed into a succession of constituent elemental areas or picture lines and are transmitted by corresponding impulse sequences.

An object of the invention is the provision in a facsimile telegraph system of a simple, reliable, and efficient instrumentality for effecting synchronization.

The above and other objects of the invention are achieved by the provision of a facsimile receiver arranged with a power-driven spiral printing edge which carries a stop arm arranged to be engaged once for each revolution by a stop member moved in the path of the stop arm under the control of a signal-responsive magnet which is deenergized intermediate each series of symbol-representing impulses and which is reenergized from the transmitter at the beginning of the next series of symbol-representing impulses for allowing an additional cycle of the printing edge. Synchronization of the apparatus is accordingly accomplished.

Reference is to be had to the accompanying drawings, in which Fig. 1 is a diagrammatic view showing how, for transmission purposes, the letter U is analyzed or scanned according to a system in which the field is subdivided into twelve parallel strips or lines; Fig. 1a is a face view of a cam disc controlling the transmission of said letter; Fig. 2 is a perspective view showing a portion of the transmitter; Fig. 3 is a perspective view showing a portion of the receiver; Figs. 1, 1a, 2, and 3 are merely illustrative of the type of printing telegraph to which my invention relates; Fig. 4 is a plan view, and Fig. 5 is a side elevation, of a printing telegraph receiver embodying my invention.

Fig. 1 shows how for instance the letter U is analyzed with the aid of twelve individual lines 1. Fig. 1a shows a disk 3 with portions 2 forming cams located at a greater distance from the center than the intervening portions 2', the several portions 2, 2' being of proper circumferential extent to operate a suitable circuit-closer, upon rotation of the cam disk, in such a manner that the periods of current impulses and of interruptions will correspond respectively to the black and the white portions of the letter U shown in Fig. 1. The shortest cam disk portions or intervals 2, 2' (current or no current respectively) occupy $\frac{1}{100}$ th of the length of the circumference of the cam disc 3 which serves to transmit the

letter and the necessary space. After the transmission of the signal impulses required to transmit the particular letter there follows a no-current interval of at least $\frac{1}{4}$ th of the circumference of the disc.

Fig. 2 shows a diagrammatic representation of a keyboard sender. On a shaft 4 which makes five revolutions per second, are arranged 48 cam discs 5 for the transmission of figures and letters. The cams 5 differ as to the arrangement of their teeth 6, such arrangement corresponding to the picture analysis of a letter, figure, or other sign. The problem now to be solved is to couple the keyboard of the sender to these discs so that at every revolution, only the picture signal of one letter is effective. To attain this a keyboard lock must be arranged so that when a key is operated, the remaining keys are locked. Only during the quarter revolution, while the space between two letters is being transmitted, are the keys unlocked. If, in this time interval, the key L, for example, is operated, an insulated distance-piece 7 is shifted to such a position that the contact springs adjacent thereto are opened and closed in accordance with the cams on the disc corresponding to the letter L. All other contact springs remain in the open condition, since their distance pieces are in the normal position under the action of the key lever springs.

The signals are sent by audible frequency alternating current so that they may easily be transmitted over any keying lines to the radio transmitter and on the other hand, to take advantage of the telephone links generally employed. The carrier frequency is 900 cycles.

The principle of operation of the receiver is shown in Fig. 3.

The essential part of the receiver is a printing spiral formed on a small roller running at 60 revolutions per second. Contact between the printing spiral 8 and the paper band or tape 9, at a speed of five letters per second, occurs twelve times from the top to the bottom and prints a line. In order to obtain immediate, visible, impression on the paper, this is covered with a thin carbon paper of the same width, which for clarity is omitted from the diagram. If the receiver is energized by a current, the receiving magnet 10 attracts its armature 11. This presses a rounded edge or platen 12 from underneath and against the paper tape 9 so that a line is recorded if the magnet 10 remains energized for the entire duration of the transmission of a line. At the next revolution the paper tape is stepped forward by $\frac{1}{100}$ th of its width.

the paper feed device 13 so that the next line occurs close to the first.

In Fig. 3 the printing spiral 8 is duplicated on the roller so that the letter picture is recorded simultaneously in two parallel lines. The purpose of this double record is to secure a synchronizing arrangement. The lines of print are accurately parallel only if the number of revolutions of the print spiral 8 is in exact accordance with the transmission time of the picture lines. If these speeds differ from one another the length of the picture lines are not parallel to the paper strip but run upwards or downwards.

The above described well-known telegraph apparatus obviates errors due to an inaccurate phase relationship of the transmitter and the receiver, by producing a double record of the letters in two parallel lines, so that at least one of the duplicate letters is recorded readably. But this method of synchronizing has the drawback that the recording cannot be supervised readily and that page printing is not possible.

It is also well known in an apparatus of this type, to transmit start-stop signals between each two successive individual letters or characters. This method of synchronizing by the transmission of a start-stop signal after the individual letters or characters is not sufficient, when the start-stop signals are disturbed by static or fadings in particular in wireless transmissions.

In accordance with the invention these disadvantages are overcome by an arrangement which in accordance with transmitted synchronization impulses momentarily checks, that is, arrests or brakes the rotating printing member or wheel after the recording of each line, in which the received letters, or other symbols are analyzed.

The rotating transmitter device includes means to transmit synchronization impulses for momentarily arresting the printing member on the receiver after each line, corresponding to the scanning of the letters or other symbols. It is useful by the fact that the stopping of the printing member is effected by a spacing signal after each line corresponding to a scanning of the letter signals, because in wireless transmission the adjustment can not be effected by a marking signal, since static can effect a stopping of the printing member.

It is also necessary that the adjustment of the phase relationship be controlled by a spacing signal in continuation of a marking signal. It is advantageous to effect the stopping of the printing member electrically or mechanically by the receiving magnet system for the direct adjustment by the receiving magnet system, a stop being arranged on the armature of receiving magnet system to arrest the printing member. It is also possible to effect the stopping by a circuit for regulating the driving motor of the

printing member which is controlled by a contact of the armature of the receiving magnet system and a second contact which is closed independently of the phase relationships of the printing member.

In Figs. 4 and 5 of the accompanying drawings the invention is illustrated in one example of construction.

The motor 4 of the receiver runs a little faster than the transmitter and drives by the friction clutch 2 the printing member 3. Underneath the printing member 3 is arranged a carbon paper 5 and the paper tape 4, which are pressed against the printing member by the edge 6 of the spring-retracted armature 7 when the magnet 8 is energized. The recording of the letters, figures and other symbols is effected in the same manner as described and shown in Fig. 3 by the co-operation of the platen-forming edge 6 of the armature with the printing member. Every letter is analyzed in lines which are nearly perpendicular to the direction of the movement of the recording paper. On the printing member 3 is arranged a stop 9, which after the scanning of one line, in this case, after one revolution of the printing member, comes against a latch 10 on the armature of the receiving magnet and the printing member is thus stopped. By a subsequent impulse the armature 7 is attracted, thus releasing the printing member for another revolution. The paper feed is effected continuously by the rollers 11 and 12.

I claim:

1. In a printing telegraph apparatus, a transmitter having means to send a series of electrical signal impulses constituting elements which collectively represent a scanning line of a symbol and to transmit synchronizing impulses intermediate successive series of line-representing impulses which are elements in the transmission of the same symbol, in combination with a receiver having a rotary printing and synchronizing member, and a single signal-responsive member responsive to all of said printing and said synchronizing impulses and cooperating with said rotary printing and synchronizing member to print or to synchronize alternatively.

2. In a facsimile receiver, a single-line rotary printing member effecting printing of a single scanning line at each revolution, a start-stop element on said rotary printing member, a signal-responsive printing member, a further start-stop element on said signal-responsive printing element, said start-stop member and said further start-stop element engageable together at each revolution of said rotary printing member in response to a received synchronizing signal to stop said rotary printing member after effecting printing of each scanning line for synchronizing.

HORST RASSOW.
